(57) **CLAIM**

The ornamental design for a ring, as shown and described.

DESCRIPTION

FIG. 1 is a top view of a ring according to my new design;

FIG. 2 is a bottom view of the ring shown in FIG. 1;

FIG. 3 is a right side view of the ring shown in FIG. 1;

FIG. 4 is a left side view of the ring shown in FIG. 1;

FIG. 5 is a front view of the ring shown in FIG. 1;

FIG. 6 is a back view of the ring shown in FIG. 1; and,

FIG. 7 is a top frontal perspective view of the ring shown in FIG. 1.

The broken lines adjacent the claimed and shaded areas represent the boundaries of the claim, and form no part thereof.

1 Claim, 7 Drawing Sheets
